UNITED STATES PATENT OFFICE

153,780

DESIGN FOR A STEAM CLEANER FOR
AUTOMOBILES OR THE LIKE

Albert C. Fletcher, Oklahoma City, Okla.

Application July 29, 1946, Serial No. 132,092

Term of patent 14 years

(Cl. D49—1)

To all whom it may concern:

Be it known that I, Albert C. Fletcher, a citizen of the United States, residing at Oklahoma City, in the county of Oklahoma and State of Oklahoma, have invented a new, original, and ornamental Design for Steam Cleaners for Automobiles or the like, of which the following is a specification, reference being had to the accompanying drawing, forming part thereof.

Fig. 1 is a perspective view looking toward one side of a steam cleaner for automobiles or the like, showing my new design.

Fig. 2 is a top plan view of the same.

The dominant feature of my design is the cylindrical main body portion of the steam cleaner and the lateral protruding member extending from adjacent the central portion of the main body portion to adjacent the top thereof, the protruding member being of a width, throughout its height, substantially equal to the diameter of the main body portion with the sides of the protruding member in substantially tangential relation to

the cylindrical main body portion, and the wall of the protruding member opposite the cylindrical main body portion being arcuate in plan.

I claim:

The ornamental design for a steam cleaner for automobiles or the like, substantially as shown and described.

ALBERT C. FLETCHER.
